UNITED STATES PATENT OFFICE.

JOSEPH F. JAWOROWSKI, OF CLEVELAND, OHIO, ASSIGNOR, BY MESNE ASSIGNMENTS, TO JOSEPH F. JAWOROWSKI AND SAMUEL DETTELBACH, BOTH OF CLEVELAND, OHIO.

ROTARY PUMP.

Application filed February 13, 1925. Serial No. 3,912.

My invention relates to an improvement in a rotary pump, particularly pumps of that type in which a sliding abutment is used, and my general object is to provide a simple and efficient organization of pump parts substantially as hereinafter shown and described and more concisely set forth in the claim.

In the accompanying drawings, Fig. 1 is a longitudinal section of the pump on line 1—1 of Fig. 2, and Fig. 2 is a vertical section thereof on line 2—2 of Fig. 1. Fig. 3 is a side elevation of the pump. Fig. 4 is a side view of the drive shaft and rotor member. Fig. 5 is a side elevation and section on line 5—5 of Fig. 1. Fig. 6 is a perspective view of the sliding abutment. Fig. 7 is a horizontal section of the pump on line 7—7 of Fig. 2. Fig. 8 is a sectional view of one of the side plates. Fig. 9 is a perspective view of the main body of the pump.

The pump comprises a main body A having flat sides 2 and a spreading base 3. The central part of the body is circular and formed with a round opening which provides a working space 4 for a rotary compression member B fixed to or forming an integral part of a drive shaft 5. This shaft is journaled in the hub portions of a pair of closure plates 6 and 7, respectively, which are adapted to be bolted 25 detachably to the flat sides 2, using a thin gasket 8 to make a tight joint therebetween. The shaft opening 9 in side plate 6 is closed and sealed at its outer end by a plug 10. The other side plate 7 has a hollow extension 11 30 adapted to confine suitable packing 12 around shaft 5. A packing gland 14 and a nut 15 may be used to compress packing 12, and a pulley or gear may be affixed to the exposed end of shaft 5 to drive the same and rotate compression member B at high speed.

Member B comprises a round enlargement 16 having an endless rib or flange 17 encircling the same at a slant or obliquely to the axis of shaft 5. Flange 17 is of a diameter 45 to fit the circular wall of working chamber 4, and the oblique position of the flange places it in touch linearly with the inner flat sides 18 of the enlarged hub portions 19—19' of closure plates 6 and 7, the engaging places 50 being diametrically opposite each other on opposite sides of the chamber. Thus flange 17 divides the chamber obliquely into two separate segmental working spaces of graduated width, and these working spaces are divided

transversely by a sliding abutment in the 55 form of a flat blade 20. The inner wall of each closure plate is formed with a vertical slot 21 adapted to hold and guide blade 20 in its reciprocable movement longitudinally of drive shaft 5. This movement is imparted by flange 17 in passing through a notch 23 in the bottom edge of the blade. The blade extends through an inverted V-shaped space 24 in body A and is held in place by a gib 25 having enlarged extremities 26 adapted 60 to prevent longitudinal shift of the gib during reciprocatory movements of the blade. The flaring space 24 provides separate inlet and outlet ducts on opposite sides of blade 20, and these ducts communicate with horizontal passages 27 and 28 which extend through screw-threaded bosses 29 to permit suitable intake and discharge pipes to be connected thereto. The base ends of the horizontal passages are reduced in diameter and curved downwardly toward the inlet and outlet ducts, and a small channel 30 is formed 65 transversely in one wall of slot 21 in each closure plate to permit the liquid to pass into upright pockets 31—31 opposite the ends of reciprocable blade 20. These pockets provide working room and equalizing pressure spaces for the blade, and the liquid displaced by the ends of the blades in entering these pockets escapes through the channels 30. The bottom edge 32 of blade 20 is curved to fit the 70 round enlargement 16 of rotor member B, and the liquid is forced to flow continuously in one direction while the drive shaft is being rotated. Thus the oblique flange in one revolution will draw in a given amount of 75 liquid on one side of the sliding abutment and discharge the same on the other side, and a uniform flow of liquid is maintained because the oblique flange provides two compression spaces of equal area and the same 80 shape diametrically opposite each other.

What I claim, is:

A rotary pump, comprising a body having a round working chamber, a blade transversely slidable of said chamber, a rotary member having an annular rib engaging said blade and dividing said chamber obliquely into separate segmental spaces, and a gib 100 for said blade removably connected to said body.

In testimony whereof I affix my signature.
JOSEPH F. JAWOROWSKI.
